[57] CLAIM

The ornament design for a keyboard skin, as shown and described.

DESCRIPTION

FIG. 1 is a top perspective view of a keyboard skin in a flexed condition;

FIG. 2 is a top plan view thereof;

FIG. 3 is a bottom plan view thereof;

FIG. 4 is a right side elevational view thereof;

FIG. 5 is a left side elevational view thereof;

FIG. 6 is a top perspective view thereof;

FIG. 7 is a bottom perspective view thereof; and,

FIG. 8 is a perspective view thereof fitted on keyboard, the broken line illustration of the keyboard forms no part of the claim design.
